UNITED STATES PATENT OFFICE.

LOUISE M. WILBER, OF BUFFALO, NEW YORK.

SCAFFOLD.

SPECIFICATION forming part of Letters Patent No. 623,269, dated April 18, 1899.

Application filed December 5, 1898. Serial No. 698,332. (No model.)

To all whom it may concern:

Be it known that I, LOUISE M. WILBER, a citizen of the United States, residing at Buffalo, in the county of Erie and State of New York, have invented new and useful Improvements in Scaffolds, of which the following is a specification.

This invention relates to a scaffold which is more especially designed for house-painters, although the same is also useful in constructing buildings.

The object of my invention is to produce a sectional scaffold for this purpose which can be easily erected for use and compactly folded for storage or transportation and which can be conveniently adjusted to suit buildings of different heights and to permit a section supporting one gang of workmen to be raised and lowered independent of the other sections.

In the accompanying drawings, consisting of two sheets, Figure 1 is a perspective view of my improved scaffold. Fig. 2 is a fragmentary vertical section, on an enlarged scale, in line 2 2, Fig. 1. Figs. 3, 4, 5, and 6 are horizontal sections in lines 3 3, 4 4, 5 5, and 6 6, Fig. 2, respectively.

Like letters of reference refer to like parts in the several figures.

The scaffold (shown in Fig. 1) consists of two sections and is arranged for painting the side of a building in two sections. In this arrangement three ladders A A' A² are placed vertically at the proper distance apart along the building, and two horizontal gang-planks or platforms B B' are employed for supporting the painters or workmen, the adjacent ends of both planks being supported from the middle ladder A', while the opposite ends of the planks are supported from the end ladders A A². Each of these ladders is constructed in the usual way, its horizontal rounds a being secured centrally to the side bars a' thereof, so as to leave the edges thereof on opposite sides of the rounds unobstructed. Each of the ladders is supported at its lower end by a standard C, which is adjustably connected with the lower portion of the ladder. This standard consists, essentially, of a horizontal base or supporting-block c and two vertical bars c' c', which have their lower diverging ends c² secured to the top of

the base. The standard-bars are connected centrally by horizontal rods or rounds c³, so as to form a downward extension of the ladder. The distance between the standard-bars is less than the distance between the ladder-bars, so that the standard-bars can be placed against the front side of the ladder-rounds, between the bars thereof.

The mechanism whereby the ladder is adjustably connected with the standard is constructed as follows: D D represent two guides which are secured to the opposite sides of the ladder-bars, near the lower ends thereof, and each of which is provided with a pair of jaws d d, which embrace the longitudinal edges of one of the standard-bars, near the upper end thereof. The space between the jaws of each guide on the inner side of each standard-bar is sufficient to permit the jaws to slide upon and down on the standard-bars when adjusting the ladder vertically without the jaws striking the rounds of the standard-bars.

When the ladder has been shifted lengthwise on the standard into the desired position, it is held against movement by a locking-pin d', which passes through one of a number of pairs of openings d² in the standard-bars and a pair of perforated supporting-arms d³, secured to the inner side of the ladder-bars and bearing against the outer side of the standard-bars, as shown in Figs. 1, 2, and 5.

The lower portion of each standard is held against displacement by means of a pair of inclined lower braces E E. These braces are preferably secured with their inner ends to the water-table of the building by screws or otherwise, and their outer ends are arranged on opposite sides of the standard and connected by a tie rod or bolt e. In order to permit the braces to be raised or lowered to suit different heights of water-tables, the outer ends of the braces are adjustably connected with the standard, so as to permit the braces to be raised or lowered on the standard. For this purpose each of the standard-bars is provided with a vertical row of adjusting-lugs f, each of which has a bayonet or undercut slot f', adapted to receive the tie-bolt of the lower braces. Each lug on one standard-

bar is horizontally in line with a lug on the other standard-bar, so that the lugs of both bars are arranged in transverse pairs. Upon shifting the tie-bolt of the lower braces from 5 one pair of adjusting-lugs to another the position of these braces with reference to the standard can be adjusted vertically to suit buildings on which the height of the water-tables varies.

10 o When the scaffold is not in use, the lower braces are detached from the standard, and the latter is detached from the ladder to permit the parts to be folded compactly.

15 The upper end of each ladder is adjustably connected with the upper portion of the building as follows: G represents a cylindrical guide socket or sleeve which is arranged above the upper end of the ladder and which is provided on opposite sides with 20 two downwardly-diverging supporting-arms g g, bearing against the inner sides of the ladder-bars. The supporting-arms are pivoted at their lower ends to the uppermost round of the ladder, which permits the guide-sleeve 25 and its arms to be folded against the ladder when not in use. The guide-sleeve and its supporting-arms are secured in an upwardly-projecting position when the scaffold is in use by means of locking-pins g' g', which 30 pass through openings in the ladder-bars and the guide-sleeve arms adjacent to the pivot of the latter.

H represents an upright pole or rod which is arranged with its central portion in the 35 guide-sleeve and is capable of sliding vertically therein. The upper end of this pole is connected by two inclined upper braces h h with the cornice-board or other part of the building. These braces are secured with 40 their inner ends to the building by screws or otherwise and are adjustably secured with their outer ends to opposite sides of the pole by a bolt h', which passes through one of a vertical row of openings h² in the pole. The 45 lower end of the pole is provided with one or more pivoted hooks h³, which are adapted to engage with one or another of the upper rounds of the ladder for holding the lower end of the pole in position. By engaging 50 the hooks h³ of the pole with a higher or lower round of the ladder and shifting the upper braces up or down on the upper end of the pole the parts may be adjusted so as to permit of attaching the upper part of the scaffold to buildings which differ in height.

I represents carriages whereby the gang planks are adjustably supported on the ladders. Each of the carriages is arranged on the outer side of one of the ladder-bars and 60 is connected near its upper and lower ends by guides i with said bar, so as to permit the carriage to slide vertically on the bar. Each of the guides consists, preferably, of two jaws which embrace the opposite longitudinal 65 edges of the ladder-bar, but are separated on the inner side of the bar sufficient to clear the

ladder-rounds and permit the carriage to rise and fall freely. Each of the guide-jaws is provided with an antifriction-roller i', which bears against the adjacent longitudinal edge 70 of a ladder-bar and permits of raising and lowering the carriage easily. The carriage is provided with a laterally-projecting supporting-bracket J, consisting of a horizontal supporting-arm j and an inclined brace j'. 75

The end of a gang-plank is placed upon the supporting-arm of the bracket and is prevented from sliding off by a stop or pin j², arranged at the outer end of the arm. When the scaffold is organized for two gang-planks, a central ladder is employed having carriages on both of its bars for supporting the opposite ends of the planks, as represented in Fig. 1. It is obvious that additional planks may be employed by providing additional ladders 80 and carriages, each intermediate ladder having two carriages, while the end ladders require only one carriage. When only one gang-plank is employed, two ladders and two carriages are required. By arranging the carriages to slide on the outer side of the ladder-bars two carriages can slide on opposite sides of the ladder without interfering with each other, thereby permitting each intermediate ladder to support two planks and still enable 95 each plank to be raised and lowered independently of the other plank.

Each of the carriages, together with the respective end of the plank resting thereon, is raised or lowered by a cord k, passing around a pulley k'. In order to utilize one cord and pulley for shifting either of the carriages on opposite sides of the same ladder, the pulley is connected with a horizontally-movable supporting-arm L, and one end of the cord is provided with a detachable fastening whereby it may be connected with either of the carriages on the ladder. This fastening consists, preferably, of a hook l, secured to the cord and adapted to engage with an opening 100 l' in the upper portion of either carriage. The supporting-arm is preferably arranged to turn upon the vertical supporting-pole below the guide-sleeve, so that it can be swung toward either side of the ladder and move the 105 pulley and its cord over the carriage which is to be shifted. The supporting-arm is held against vertical movement on the pole by pins l², passing through openings in the pole above and below the arm, a vertical row of 110 such openings being provided to permit of adjusting the arm vertically on the pole and a washer l³ being interposed between each pin l² and the adjacent side of the arm to provide a large bearing-surface.

115 Each of the carriages is held in its adjusted position by an automatic catch or pawl M of usual construction, pivoted to the inner side of the carriage, preferably on one of its guides, and provided at one end with a slot or mouth 120 m, which engages with one of the rounds of the ladder, and at its opposite end with a

weight m' , whereby the catch is turned for automatically engaging its mouth with said rounds in a well-known manner.

The side bars of the standard are separated 5 from the side bars or the ladder, and the distance from the lower ends of the ladder-bars to the base or to the ground is greater than the height of the carriages to permit the same to be applied to the ladder from the lower 10 end of the side bars or removed therefrom, thereby permitting the scaffold to be erected or taken down more easily and also permitting one of the two carriages to be removed from a ladder when it is desired to take down 15 the scaffolding partially and erect the same elsewhere.

When it is desired to paint the opposing sides of two buildings simultaneously, the ladders are erected in the alley-way or space 20 between the two buildings, and an additional bracket n is attached to each carriage for carrying another gang-plank n' , as represented in dotted lines, Figs. 2 and 3, the brackets of each carriage projecting laterally 25 in opposite directions and supporting the planks on opposite sides of the ladder.

My improved scaffold is very durable in construction and reliable in operation and can be quickly erected and adjusted, thereby 30 permitting the building to be painted expeditiously, whereby the cost of painting the building is reduced proportionately.

I claim as my invention—

1. The combination with the standard and 35 the ladder of a scaffold, of a guide arranged on the ladder and embracing the standard, a supporting-arm arranged on the ladder adjacent to the standard, and a pin passing through openings in the standard and the 40 supporting-arm of the ladder, substantially as set forth.

2. The combination with the standard of the scaffold provided with a pair of upright bars, of a ladder provided near its lower end with 45 a pair of guides which loosely embrace the bars of the standard, supporting-arms arranged on the ladder adjacent to the outer side of the standard-bars, and a locking-pin passing through openings in the standard-bars and in said arms of the ladder, substantially as set forth.

3. The combination with the standard of the scaffold provided with a vertical row of undercut notches, of a brace adapted to engage 55 with one or the other of said notches, substantially as set forth.

4. The combination with the standard of the scaffold, of lugs arranged in vertical rows on the standard and each provided with an undercut slot, braces arranged on opposite sides of the standard, and a tie-rod connecting said braces and engaging with the slots of a pair of said lugs, substantially as set forth.

5. The combination with the ladder of the scaffold adapted to support a gang-plank, of

an upright supporting-pole connected with the upper central portion of the ladder, and braces connected with said pole, substantially as set forth.

6. The combination with the ladder of the scaffold provided at its upper end with a guide-sleeve, of a supporting-pole capable of vertical adjustment in said sleeve, and braces connected with said pole, substantially as set forth. 75

7. The combination with the ladder of the scaffold provided at its upper end with a guide-sleeve, of a supporting-pole capable of vertical adjustment in said sleeve, a hook arranged on the lower portion of the pole and 80 engaging with one of the rounds of the ladder, and braces connected with the upper end of the pole, substantially as set forth.

8. The combination with the ladder of the scaffold, of a guide-sleeve arranged above the ladder and provided with supporting-arms which are pivoted to the ladder, a supporting-pole capable of sliding in said sleeve, a hook connected with the lower portion of the pole and engaging with one of the rounds of the ladder, and braces connecting with the upper portion of the pole, substantially as set forth. 85

9. The combination with the ladder of a scaffold, of two separate carriages which are mounted on the side bars of the ladder and 90 which are capable of moving vertically the full height of the side bars, whereby two separate platforms resting on the carriages may be raised and lowered independently of each other and one ladder serves to support the 100 opposing ends of two separate platforms, substantially as set forth.

10. The combination with the ladder of the scaffold, of two plank-supporting carriages capable of independent vertical movement on 105 opposite sides of said ladder, a shifting rope adapted to be connected with either of said carriages and passing around a pulley, and a movable support carrying said pulley, substantially as set forth. 110

11. The combination with the ladder of the scaffold, of two plank-supporting carriages capable of independent vertical movement on opposite sides of said ladder, a shifting rope adapted to be connected with either of said 115 carriages and passing around a pulley, an upright supporting-pole connected with said ladder, and a horizontally-swinging arm pivoted on said pole and carrying said pulley, substantially as set forth. 120

12. The combination with the ladder of the scaffold and the plank-supporting carriage guided on said side bars of the ladder, of a standard which supports said ladder so that the lower ends of its side bars are arranged 125 above the ground a distance greater than the height of the carriage to permit the latter to be placed upon said side bars from the lower end thereof or removed therefrom, substantially as set forth. 130

13. The combination with the ladder of the scaffold and the plank-supporting carriages guided on the side bars of the ladder, of a standard having its upper portion narrower than the width of the ladder and connected with the same, the lower end of said side bars being separated from the ground a distance greater than the height of the carriages to permit the latter to be placed upon the side

bars or removed therefrom at the lower ends to of the side bars, substantially as set forth.

Witness my hand this 23d day of November, 1898.

LOUISE M. WILBER.
